Patented Jan. 20, 1920.

UNITED STATES PATENT OFFICE.

BENTLEY A. PLIMPTON, OF VICTOR, NEW YORK.

INSULATOR-SUPPORT.

1,328,687.

Specification of Letters Patent. Patented Jan. 20, 1920.

Application filed October 31, 1917. Serial No. 199,579.

To all whom it may concern:

Be it known that I, BENTLEY A. PLIMPTON, of Victor, in the county of Ontario and State of New York, have invented certain new and useful Improvements in Insulator-Supports; and I do hereby declare the following to be a full, clear, and exact description of the same, reference being had to the accompanying drawings, forming a part of this specification, and to the reference-numerals marked thereon.

My invention relates to insulator supports, and especially to the class known as pin supports involving generally some form of attaching means for securing a pin upon a cross arm, and provision for retaining the insulator upon the upper end of the pin in such manner as to allow for expansion and contraction without destructively affecting the insulating material. An equally important purpose of the improvement is to afford an economical arrangement which can be manufactured and assembled with a minimum expense, and which also serves to provide an extremely rigid device capable of withstanding great strains. To these and other ends the invention consists in certain improvements and combinations of parts, all as will be hereinafter more fully described, the novel features being pointed out in the claims at the end of the specification.

In the drawings:

Figure 1 is a vertical sectional view of an insulator and pin support, with my invention incorporated, and

Fig. 2 is a sectional view of the pin.

Similar reference numerals in the several figures indicate the same parts.

The structure shown includes a more or less conventional and well known means of attaching the insulator to a support, consisting of the usual cross arm or similar part 1, upon which is arranged a tapered truss member 2 of hollow formation, to receive the body portion 3 of the pin. The latter passes through an opening 4 in the cross arm and is threaded at its lower end to receive the retaining nut 5.

The novel part of the structure resides in the means for supporting the pin upon the truss member 2 and for securing the insulator in place on the pin. To this end, the pin includes an enlarged upper end 6 which is formed integral with the body portion 3 and threaded exteriorly. The threaded upper end or thimble engaging portion 6 co-

operates with the insulator 7, which is of the usual type, and formed of porcelain or other non-conducting material. The insulator carries a thimble 8 which is preferably cemented or otherwise permanently attached to it, and is threaded interiorly to engage the threaded portion 6 on the pin.

9 designates a collar or shoulder permanently attached to the pin 3, and preferably formed integral therewith. The collar 9 is arranged beneath the thimble engaging portion 6, and rests upon the upper end of the truss member 2. The collar 9 is provided on its upper side with an inclined surface 10, against which the outer edge 11 of the thimble 8 abuts, when the insulator is fully threaded on the pin. This makes it possible to obtain a tight connection between the thimble and the pin as the lower end of the thimble is forced tightly against the inclined surface 10, setting up a jamming action between the threads on the thimble and the threads on the pin. The innermost end of the thimble 12 extends slightly beyond the threaded portion, and slightly beyond the inner end 13 of the pin when the latter is fully engaged, affording a space 14 between the parts. This gives sufficient clearance to permit the outer edge of the thimble to wedge tightly against the inclined surface 10 of the collar, and to also allow for the necessary expansion and contraction of the pin, without having it injure the porcelain.

By this arrangement, a very simple and cheap construction is afforded, and one which will withstand very heavy strains without causing an appreciable deflection of the pin, and any expansion of the latter is taken care of, so as not to seriously affect the insulating member, which at the same time is held rigidly under all conditions.

I claim as my invention:

1. The combination with a threaded insulator thimble, of a pin having an integral threaded thimble portion at its upper end, a rigid collar on the pin beneath the thimble portion and having an upper surface against which the outer end of the thimble engages, a hollow truss member abutting the underside of the collar out of contact with the thimble and on which the collar rests and through which the body portion of the pin extends, a support for the truss member, and retaining means attached to the pin on the underside of the support.

2. The combination with a threaded insu-

lator thimble, of a pin having an integral threaded thimble portion at its upper end, a collar permanently attached to the pin beneath the thimble portion and having an upper inclined surface against which the outer end of the thimble engages, a hollow truss member on which the collar rests and through which the body portion of the pin extends, a support for the truss member, and retaining means attached to the pin on the under side of the support.

3. The combination with a threaded insulator thimble, the innermost end of which extends slightly beyond the threads to afford

a space between the end of the thimble and 15 the end of a pin when threaded therein, of a pin having an integral threaded thimble portion at its upper end, a collar integrally attached to the pin beneath the thimble portion and having an upper inclined surface against 20 which the outer end of the thimble engages, a hollow truss member on which the collar rests and through which the body portion of the pin extends, a support for the truss member, and retaining means attached to the 25 pin on the under side of the support.

BENTLEY A. PLIMPTON.
